H. WALLACE,

CARTRIDGE SHELL EXTRACTOR.
APPLICATION FILED FEB. 9, 1918.

1,275,803.

Patented Aug. 13, 1918.

UNITED STATES PATENT OFFICE.

HERBERT WALLACE, OF SPRINGFIELD, MASSACHUSETTS, ASSIGNOR, BY MESNE ASSIGNMENTS, TO UNITED STATES MACHINE GUN COMPANY, OF BOSTON, MASSACHUSETTS, A CORPORATION OF MASSACHUSETTS.

CARTRIDGE-SHELL EXTRACTOR.

1,275,803.

Specification of Letters Patent. Patented Aug. 13, 1918.

Application filed February 9, 1918. Serial No. 216,146.

To all whom it may concern:

Be it known that I, HERBERT WALLACE, a citizen of the United States of America, and a resident of Springfield, county of Hampden, and State of Massachusetts, have invented an Improvement in Cartridge-Shell Extractors, of which the following description, in connection with the accompanying drawings, is a specification, like characters on the drawings representing like parts.

Ordinarily the automatic extractor with which modern rifles or other firearms are provided extract the exploded shell without difficulty. It sometimes happens, however, that, owing to breakage due to the explosion or some inherent weakness or other cause, the automatic extractor, which, as is well known, grips the head of the cartridge at the rim, withdraws only the head or rear part of the exploded shell, leaving the rest of the shell in the cartridge chamber, generally beyond the reach of said automatic extractor, which thus becomes useless for the time being. Until the remainder of the shell thus left in the gun is removed, the gun is useless, as a fresh cartridge cannot be inserted in the cartridge chamber until the latter is cleared.

My invention aims to provide an extractor which will enable the broken shell to be quickly and surely removed, and this without injury to the gun and without expenditure of unnecessary force.

The features and aims of my invention will be best understood from the following description, taken in connection with the accompanying drawings of one preferred embodiment of the invention, the invention in its true scope being set forth by the claims.

In the drawings:

Figure 1 is a plan view, partly in section, of the breech portion of a rifle showing the cartridge chamber, automatic extractor and a broken cartridge shell in the cartridge chamber, together with the illustrative embodiment of my invention herein described, in place ready to function;

Fig. 2 is an elevation of the illustrative embodiment of my invention herein described;

Fig. 3 is a longitudinal section of the em-

bodiment of the invention shown in Fig. 2, and

Fig. 4 is a cross-section on line 4—4 of Fig. 3.

The illustrative embodiment of the invention herein shown is adapted to be inserted from the breech into the broken cartridge shell, until its forward end has emerged from the forward end of the latter, said forward end being provided with means to engage the forward edge of the shell when thus inserted, so that when the device is withdrawn, it will, by said engagement with the forward edge of the shell withdraw the latter with it, means being provided to lock said shell-edge-engaging means in position to maintain its engagement with the forward edge of the shell during such withdrawal. At its rear end the device is provided with means to be engaged by the automatic extractor of the gun or rifle and preferably with means to prevent the device from being inserted too far, or driven into the breech by the extractor when used in a firearm using rimless cartridges, such as the Springfield rifle used in the United States Army.

Referring more particularly to Fig. 1 of the drawings, the illustrative embodiment of my invention comprises a rod 2 having one end 4 removably secured in a plug 6 by screw-threaded engagement with a screw-threaded bore 8 provided centrally of the latter. The plug 6 is provided with an externally tapered sleeve-like extension 10 surrounding the rear portion of the rod 2.

At its forward end the rod 2 is provided with a conical portion 12 terminating in a head 14, for a purpose hereinafter more fully described, said head being provided with a shoulder 16 at its junction with said conical portion 12. The rod 2 is surrounded by a sleeve of spring metal 18, having its rear portion 20 received within the sleeve-like extension 10 of the plug 6 when the device is assembled, said sleeve and rod being relatively movable longitudinally and said extension 10 acting as a guide for said sleeve. Said sleeve 18 is provided with two or more, herein three, longitudinal slots 21, extending from its forward end backward to within a suitable distance of its

rear end 20. At the forward end of the sleeve 18 the walls of the latter are somewhat thickened to form the head 22 having the rearwardly facing shoulder 24. There is sufficient clearance between the walls of the sleeve and the rod to enable the normally expanded forward portion of said sleeve to be contracted about said rod, by pressure exerted laterally upon the head 22 thereof. This clearance is secured without reducing the diameter or strength of the rod or stem 2, by tapering or flaring the bore of the sleeve at its forward end, this also resulting in making the end portion of the sleeve relatively more resilient than the mid portion thereof.

The head 14, as shown, is rounded or beveled from its tip toward its sides and rear and presents to the walls of the cartridge shells, when it is inserted therein, a smooth unyielding and unshouldered penetrating tip adapted to open up a passage-way for the split-head 22, the forward end of which is shown as of substantially the same diameter as the head 14. At its rear end the plug 6 is provided with a collar 26 to be engaged by the automatic extractor of the gun or rifle, and preferably also with a stop collar or shoulder 28, to limit the penetration of the device into the cartridge chamber, the device being of such a length that when the stop 28 abuts against the forward end wall 30 of the breech, Fig. 1, the shoulder 24 will be outside the forward end of the exploded shell. The collar 26 should be of substantially the same diameter as the corresponding part on the shell to be exploded. The stop-shoulder 28 will be at such a distance from the collar 26 that the latter will be sufficiently spaced from the end wall 30 of the breech to be readily seized by the automatic extractor of the firearm, said collar 26 occupying then substantially the same position that the corresponding rim or collar of a cartridge would occupy when the latter is in the cartridge chamber.

In Fig. 1 the usual automatic extractor is shown said extractor being of well-known and usual construction and consisting briefly of a member 32 of resilient metal extending along the breech bolt 34 to which it is revolvably secured by a collar 36 at a point intermediate the two free ends of said extractor. The forward end of the automatic extractor is provided with a beveled lip 38, which may be said to constitute the extractor proper. When the breech bolt is pushed forward to drive a cartridge home into the cartridge chamber, the lip 38 yields away from the breech bolt, on encountering the rear rim of the cartridge, owing to the resiliency of the member 32, and the lip 38 snaps over said rear rim of the cartridge shell, or in the case of a rimless cartridge, over the narrower rear collar of the cartridge shell and

into the annular groove just in front of said collar, so that when the breech bolt is thrown back to open the breech, the automatic extractor 38 draws the empty shell out of the cartridge chamber.

The operation of my novel extractor is as follows: Assuming that on opening the breech it is found that the cartridge shell 42 is broken within the chamber, as shown by the dotted line 40 in Fig. 1, for example, so that it cannot be extracted by the automatic extractor 38, my improved extractor is placed in the breech and the breech bolt is thrown forward, closing the breech. In this operation the device will be driven forward into the cartridge chamber and inside the broken shell, until the stop 28 abuts against the end wall 30 of the breech. In this operation the normally expanded front end 22 of the resilient split sleeve 18, by its engagement with the inner wall of the shell, will momentarily arrest the forward movement of said sleeve 18 until the conical portion 12 of the rod 2 has moved out of the front end of the sleeve 18 and the rear end of the latter is encountered by the bottom of the sleeve-like extension 10 of the plug 6, whereupon said sleeve will be compressed by the engagement of its front end 22 with the inner wall of the shell, and the sleeve will move forward with the rod 2. About the time the stop 28 arrests the further entrance of the device into the cartridge chamber, the front end 22 emerges from the front end of the shell and expands by its spring action, so that the shoulder 24 is in front of the front edge of the shell. In driving the device home into the cartridge chamber, the automatic extractor 38 has snapped over the annular collar 26 and into the annular space between said collar and the stop 28. If now the breech bolt be drawn back to open the breech in the usual way, the automatic extractor will withdraw the device from the cartridge chamber. In this operation the rod 2 will first be drawn backwardly relatively to the sleeve 18, the latter being temporarily held against rearward movement by engagement of its shoulder 24 with the front edge of the exploded shell; until the conical portion 12 of said rod has entered the conical opening in the front end 22 of the sleeve and the shoulder 16 of the head 14 of the rod has engaged the front edge of portion 22 of the sleeve 18, whereupon in the continued rearward movement of the device under the action of the automatic extractor 38, the sleeve 18, and with it the broken shell, will be withdrawn, since the conical part 12 of the rod head 14 locks the front end of the sleeve 18 against contraction, so that the shoulder 24 cannot release the front edge of the exploded shell.

The rounded or beveled front end of the head 14 presents an unyielding, penetrative,

and unshouldered guide for the extractor. This is adapted to enter a contracted opening, such as may be formed by jagged, split, or inwardly flared or bulging walls of the 5 broken cartridge shell, and to force its way between such walls, expanding or spreading them without catching thereon, thus opening a passage and clearing the course for the succeeding resilient, shouldered, front end 10 of the sleeve.

It will also be noted that the head 14 of the rod 2 fits the bore of the barrel. The effect of this is to maintain the whole device, and more particularly the rod 2 and head 15 22, centered during the operation of the device in withdrawing the broken shell, thus assuring a proper and adequate engagement of the shoulder 16 with the front edge of the head 22 and of the shoulder 24 with the 20 front edge of the broken cartridge shell. In the absence of the guide 14, the device, and particularly the front end of the rod 2, would be liable to deviate from their true axial position in the cartridge chamber during 25 the operation of the device, such tendency to deviate from their axial position being due in part to the fact that the automatic extractor of the fire-arm engages and exerts its rearward pull upon one side only 30 of the collar 26. Where such deviation occurs there is an absence of a proper co-operation of the shoulder 16 with the front edge of the sleeve 18 and of the shoulder 24 of the resilient head 22 with the front edge of 35 the broken cartridge shell. Such deviation is also liable to cause the device to bind in the cartridge chamber. The result is that the automatic extractor is liable to release the collar 26 without withdrawing the device, or the device is withdrawn without 40 the broken cartridge shell.

The expansion or spreading apart of the inwardly flared or obstructing shell walls by the passage of the head 14, and the shouldered end 22 of the sleeve, is followed by the entrance of the sleeve 10, the tapered shape of which further expands and opens the passageway for the plug 6, permitting the entrance of the extracting device into 50 the broken cartridge shell for the full required depth without conflict with the broken fragments or flared or bulging portions thereof.

It will be noted that the part 12 of the 55 rod head 14, and the front portion 22 of the sleeve, are so shaped that the part 12 in entering the expanded front portion of the sleeve when the device is operated will not further expand the front portion of the sleeve but will simply lock it against contraction. This prevents undesirable outward pressure by the head 22 on the inner surface of the barrel when the shell is extracted.

65 While I have herein described one spe-

cific embodiment of my invention, it is to be understood that the invention is not to be considered as limited to the details described, nor any of them, but that said embodiment may be variously modified within the true 70 scope of my invention, which is more particularly set forth in the claims.

Claims:

1. A device for extracting broken cartridge shells from firearms, said device being 75 adapted to be inserted into the broken shell lodged in the cartridge chamber, and comprising, in combination, resilient means adapted to pass through the broken cartridge shell, when the device is inserted into 80 the latter, and to engage the front edge of said broken cartridge shell; means to lock said resilient means in engagement with the front edge of the cartridge shell; guide means to fit within the barrel in advance of 85 the cartridge chamber to guide and center said device when the latter is operated, and means to be engaged by the automatic extractor of the firearm whereby when said automatic extractor is operated it will extract 90 said device and broken shell from the cartridge chamber.

2. A device for extracting broken cartridge shells from firearms, said device being adapted to be inserted into the broken 95 shell lodged in the cartridge chamber and comprising, in combination, resilient means adapted to pass through the broken cartridge shell when said device is inserted into the latter, and to engage the front edge of 100 said shell, means to lock said resilient means against contraction when moved into engagement with the front edge of the cartridge shell without further expanding said resilient means; guide means to fit within 105 the barrel in advance of the cartridge chamber to guide and center said device when the latter is operated, and means to be engaged by the automatic extractor of the firearm whereby when said automatic extractor is 110 operated it will extract said device and cartridge shell from the cartridge chamber without further expanding said device.

3. A device for extracting broken cartridge shells from firearms, said device being 115 adapted to be inserted into the broken shell lodged in the cartridge chamber and comprising, in combination, a split sleeve of resilient material adapted to extend through the broken cartridge shell, when said device 120 is inserted in the latter, a shoulder adjacent the front end of said sleeve to engage the front edge of the broken shell; a rod extending through said sleeve and movable lengthwise relatively to the latter, a collar 125 provided upon said rod adjacent its rear end to be engaged by the automatic extractor of the firearm, a stop upon said rod adjacent said collar to limit the penetration of the device into the cartridge chamber, a 130

head provided upon said rod adjacent its front end fitting the bore of the barrel and providing a centering guide thereon for the extracting device, said head having a locking part to fit within the shouldered front end of said split sleeve without further expanding the same, and a shoulder to engage the front edge of said sleeve, whereby when said automatic extractor is operated after engaging said collar, it will draw said rod backwardly relatively to said sleeve and axially of the latter to cause said locking part to enter the front end of the sleeve and lock the shoulder of the latter in expanded engagement with the front edge of the broken cartridge without further expanding said sleeve and bring the shoulder of said rod into engagement with the front edge of said sleeve, whereupon continued operation of said automatic extractor will withdraw said device and with it the broken shell from the cartridge chamber.

4. A device for extracting broken cartridge shells from fire-arms, said device being adapted to be inserted in the broken cartridge shell lodged in the cartridge chamber, and comprising, in combination, resilient means adapted to pass through the broken cartridge shell, when said device is inserted into the latter, and to engage the front edge of said shell; means to lock said resilient means in engagement with the front edge of the cartridge shell; an unyielding, penetrating guide member having smooth, beveled walls adapted, as the device is inserted into the broken cartridge shell, to penetrate the passage in advance of said resilient means and force open said passage; and means to be engaged by the automatic extractor of the fire-arm whereby, when said automatic extractor is operated, it will extract said broken shell from the cartridge chamber.

5. A device for extracting broken cartridge shells from fire-arms, said device being adapted to be inserted in the broken cartridge shell lodged in the cartridge chamber, and comprising, in combination, a split

sleeve of resilient material having a shouldered portion adjacent the front end to engage the front end of the broken shell; a rod extending through said sleeve and movable lengthwise relatively to the latter, said rod being provided adjacent its front end with a guide head having smooth beveled walls to penetrate the walls of the broken cartridge shell, as the device is inserted into the latter, and open a passage for the sleeve, and with a locking part to fit within the shouldered front end of the sleeve, when said rod is drawn rearwardly, and lock the front end of said sleeve against contraction; a plug to which the rear end of said rod is detachably secured, said plug presenting means adapted to be engaged by the automatic extractor of the fire-arm, and a tapered front portion adapted also to penetrate and spread the walls of the broken cartridge shell when said device is inserted into the latter.

6. A device for extracting broken cartridge shells from fire-arms, said device comprising a tapered plug having means connected therewith to be engaged by the extractor of the fire-arm; a stem detachably secured thereto and carrying at its forward end a guiding head having smooth beveled walls adapted to penetrate and spread apart the walls of the broken cartridge shell and open a passage through the latter; and extracting means having relative movement on said stem and presenting resilient members with shouldered portions adapted to yield and pass through the front portion of the cartridge shell but thereafter to expand and position said shouldered portions in advance of the front edge of the cartridge shell, said stem presenting to said resilient members a locking formation and adapted when retracted to lock said expanded shouldered portions of said resilient members against further contraction.

In testimony whereof, I have signed my name to this specification.

HERBERT WALLACE.
